UNITED STATES PATENT OFFICE.

ALFRED H. HUMPHREY, OF NEW YORK, N. Y., ASSIGNOR TO GENERAL GAS LIGHT COMPANY, OF KALAMAZOO, MICHIGAN.

GAS-STOVE.

1,373,562.

Specification of Letters Patent.

Patented Apr. 5, 1921.

Application filed October 16, 1917. Serial No. 196,861.

To all whom it may concern:

Be it known that I, ALFRED H. HUMPHREY, a citizen of the United States, residing at New York, county of New York, 5 State of New York, have invented certain new and useful Improvements in Gas-Stoves, of which the following is a specification.

This invention relates to improvements in gas stoves.

10 The main objects of this invention are:

First, to provide an improved gas stove which is very efficient in the matter of heat radiation.

Second, to provide an improved gas stove 15 which is well adapted for use in grates or fireplaces.

Third, to provide an improved gas stove in which the parts are so formed and assembled that the design may be readily 20 changed.

Fourth, to provide an improved gas stove having these advantages which is comparatively simple and economical in structure.

25 Further objects, and objects relating to structural details, will definitely appear from the detailed description to follow.

I accomplish the objects of my invention by the devices and means described in the following specification. The invention is 30 clearly defined and pointed out in the claims.

A structure which is a preferred embodiment of my invention is clearly illustrated in the accompanying drawing, forming a part of this specification, in which:

35 Figure I is a front elevation of a structure embodying the features of my invention, a portion of the radiating elements being omitted and those shown illustrated more or less conventionally, a pair of detached legs being shown which may be substituted for the attached pair.

40 Fig. II is a detail vertical transverse section on a line corresponding to line 2—2 of Fig. I.

45 Fig. III is a detail transverse vertical section on a line corresponding to line 3—3 of Fig. I.

50 Fig. IV is a front perspective view with the top bar, fireback, and radiating elements removed.

Fig. V is a detail horizontal section on a line corresponding to line 5—5 of Fig. I.

Fig. VI is a detail vertical section on a line corresponding to line 6—6 of Fig. I.

55 Fig. VII is a detail section on a line cor-

responding to line 7—7 of Figs. II and III, showing details of the mounting of the supporting plate.

Fig. VIII is a detail vertical section on a line corresponding to line 8—8 of Fig. V, 60 showing details of mounting the burner.

Fig. IX is a detail horizontal section on a line corresponding to line 9—9 of Fig. I, illustrating the manner of attaching the second pair of front legs shown in Fig. I.

65 Fig. X is a detail section through the legs of Fig. IX on a line corresponding to line 10—10 of that figure.

Fig. XI is a detail vertical section on a line corresponding to line 11—11 of Fig. V, 70 showing the method of attaching one of the rear legs.

Fig. XII is a detail vertical section on a line corresponding to line 12—12 of Fig. V, 75 showing details of the leg attaching means.

Fig. XIII is a detail plan view partially in section, showing the arrangement of the top bar.

In the drawing similar reference characters refer to similar parts throughout the 80 several views, and the sectional views are taken looking in the direction of the little arrows at the ends of the section lines.

Referring to the drawing, the back wall 1 and side walls 2 are, in the structure illustrated, formed of sheet metal and in one 85 piece.

The side walls are provided with outwardly turned flanges 3 at their front edges to which are attached uprights 4. These 90 uprights are preferably castings and may be ornamented as desired.

The uprights, for the purpose of lightening them, are cored out at 5 on the rear side, leaving cross pieces 6 at intervals adapted to receive the attaching screws 7 disposed through the wall flanges. The lower ends of the uprights and the front bar 8 are rigidly secured together by the screws 9 and 9'. The screws 9 are arranged through the side 100 wall flanges and the uprights to engage the front bar, as shown in Fig. VI. This front bar may also be ornamented as desired and made to harmonize with the uprights. The rear and side walls are reinforced at their 105 lower ends by the strap 10.

The rear legs 11 have angled seats 12 therein for the rear corners and are secured by means of the screws 13. The front legs 14 are secured to the under sides of the 110

front piece by means of the screws 15. If desired, these legs may be removed and andiron like legs, which are provided with arms 16, may be attached. The arms 16 are 5 adapted to fit into the recesses 17 in the ends of the front bar and secured thereto by means of the screws 18.

The structure is considerably changed in 10 appearance merely by changing the legs. However, the front bar and the uprights 15 may be changed as desired.

The uprights are further connected by the top bar 19, which may be suitably ornamented, and the intermediate cross bars 20. 15 A supporting plate 21 is mounted within the walls, it being secured to the rear walls by the screws 22 and to the uprights by screws 23. This plate has a forwardly projecting portion 24 which constitutes a 20 hearth. The front edge of the plate 21 is below the top flange 25 of the front plate,—see Fig. II. The supporting plate thus serves as a bracing member for the walls and uprights as well as to support the parts 25 mounted thereon.

The fireback 26 is mounted upon this plate, which has a rib 27 in front of the fireback. The upper end of the fireback is engaged by the yoke-shaped top member 28, 30 which fits upon the upper edges of the walls and is secured to the rear walls by the screws 29 and to the uprights by the ears 30,—see Fig. VI. This frame member overlaps the fireback resting upon the top thereof so that 35 the fireback is effectively retained on its seat on the supporting plate.

The side members of the top bar have 40 downwardly projecting lugs 31 which engage the front of the fireback preventing its tilting forward.

The supporting plate 21 has a series of 45 burner openings 32 therein. Above these openings I arrange the tubular radiating elements or radiants 33. The bottom of these radiants are retained and positioned by the rib 27 and a rib or flange 34 and the lugs 35,—see Figs. II and V.

The fireback has a portion 36 at its upper 50 end which overhangs the upper ends of the radiants, the overhang being close thereto. This serves to deflect the heat forward and further adds to the uniformity of the heating of the radiants and in the general efficiency of the structure, as is described in my 55 application for Letters Patent, filed May 18, 1916, Ser. No. 98337. The upper ends of the radiants are retained by the bail-shaped rod 37 which is pivoted in the end walls so that it may be swung down in front of the 60 radiants, as shown in the drawing, or may be swung up to permit their easy removal or replacement.

The burner, designated generally by the 65 numeral 38, is mounted on lugs 39 depending from the supporting plate. The burner has

a plurality of tips 40 supported in alignment with the burner openings 32. The stem 41 for the gas control valve projects forwardly so that it may be manipulated from the front.

70

My improved gas stove is highly efficient and at the same time is comparatively simple and economical in structure. The parts are so assembled that the design may be greatly varied, that is, a different design 75 of top bar, uprights, front bar, and front legs, may be used with the other parts. This is of very material advantage, as it avoids the necessity for great variety of general structures, and at the same time it 80 makes it possible to provide changes in design.

The parts are comparatively simple and economical to produce and they may be very easily assembled.

85

I have illustrated my improvements in one form in which I have embodied the same. I have not attempted to illustrate or describe other modifications and adaptations, as I believe the disclosure made will enable those 90 skilled in the art to which my invention relates to embody or adapt the same as may be desired.

Having thus described my invention, what I claim as new and desire to secure by Letters Patent, is:

95

1. In a gas stove, the combination of rear and side walls, corner uprights secured to the front edges of the side walls, a front bar secured to the lower ends of said uprights, 100 a supporting plate having burner openings therein disposed within and mounted on said walls and uprights, radiating elements mounted on said plate above said burner openings, a fireback mounted on said plate 105 at the rear of said radiating elements, said plate being provided with retaining and positioning members for said radiating elements and fireback, a top bar disposed on said walls and secured thereto and to said 110 corner uprights to engage the top of said fireback and having lugs projecting downwardly at the front thereof, and a burner supported within said walls below said plate and provided with burner tips aligned with 115 said burner openings.

2. In a gas stove, the combination of sheet metal rear and side walls, corner uprights secured to the front edges of the side walls, a front bar secured to the lower ends of said 120 uprights, a supporting plate having burner openings therein disposed within and mounted on said walls and uprights, radiating elements mounted on said plate above said burner openings, a fireback mounted on said plate at the rear of said radiating elements, a top bar disposed on said walls and secured thereto and to said corner uprights 125 to engage the top of said fireback in a spaced relation to its face, and a burner supported 130

within said walls below said plate and provided with burner tips alined with said burner openings.

3. In a gas stove, the combination of sheet metal rear and side walls, corner uprights secured to the front edges of the side walls, a front bar secured to the lower ends of said uprights, a supporting plate having burner openings therein disposed within and mounted on said walls and uprights, radiating elements mounted on said plate above said burner openings, a fireback mounted on said plate at the rear of said radiating elements, a top bar disposed on said walls and secured thereto and to said corner uprights to engage the top of said fireback in a spaced relation to its face, a bail-shaped retaining bar for the upper ends of said radiating elements pivoted on the end walls to be swung to and from retaining position, and a burner supported within said walls below said plate and provided with burner tips alined with said burner openings.

4. In a gas stove, the combination of a rear wall and side walls having out-turned flanges at their front edges, corner uprights secured to said flanges, a front bar secured at the lower ends of said uprights, a supporting plate disposed within said walls and secured thereto and to said uprights, a fireback mounted on said plate, and a top bar disposed on said walls and secured thereto and to said corner uprights to engage the top of said fireback and having lugs projecting downwardly at the front thereof.

5. In a gas stove, the combination of a sheet metal rear wall and side walls having out-turned flanges at their front edges, corner uprights secured to said flanges, a front bar secured at the lower ends of said uprights, and a supporting plate disposed within said walls and secured thereto and to said uprights.

6. In a gas stove, the combination of a sheet metal rear wall and side walls having out-turned flanges at their front edges, corner uprights secured to said flanges, a front bar secured at the lower ends of said uprights, and a supporting plate disposed within said walls and secured thereto and to said uprights, said plate having a hearth portion extending forwardly to said front bar.

7. In a gas stove, the combination of sheet metal rear wall and side walls having flanges at their front edges, uprights secured to said flanges, a front bar secured at the lower ends of said uprights, and a supporting plate disposed at the rear of said front bar within said walls and secured thereto.

8. In a gas stove, the combination of sheet metal rear and side walls, corner uprights secured to the front edges of the side walls, a front bar secured to the lower end of said uprights, a front plate disposed within said walls and mounted thereon and having burner openings therein, and a burner suspended from said supporting plate within said walls and provided with burner tips alined with said burner openings.

9. In a gas stove, the combination of sheet metal rear and side walls, corner uprights secured to the front edges of said side walls, a front bar secured to the lower ends of said uprights, and two sets of legs, one set being adapted to be disposed below said front part and the other at the ends thereof, said front part being adapted at its under side and ends to receive independent leg attaching members so that either style of leg may be attached.

10. In a gas stove, the combination of sheet metal rear and side walls, corner uprights secured to the front edges of the side walls, a front bar secured to the lower ends of said uprights, a supporting plate having burner openings therein disposed within said walls and mounted thereon and on said uprights, and a burner suspended from said supporting plate within said walls and provided with burner tips alined with said burner openings.

11. In a gas stove, the combination of a sheet metal rear wall and side walls having out-turned flanges at their front edges, corner uprights secured to said flanges, a front bar secured to the lower ends of said uprights and adapted to receive leg attaching members, and a supporting plate having burner openings therein disposed within said walls and mounted thereon and on said uprights, said plate having a hearth portion extending forwardly to said front bar.

12. In a gas stove, the combination of integral sheet metal rear and end walls, uprights to which the front edges of the end walls are secured, a front bar secured to the uprights, front legs on said front bar and rear legs on said walls, and a supporting plate disposed within said walls and secured thereto.

In witness whereof, I have hereunto set my hand and seal in the presence of two witnesses.

ALFRED H. HUMPHREY. [L.S.]
